(57) **CLAIM**

The ornamental design for a handheld ultrasonic display device with cover, as shown and described.

DESCRIPTION

FIG. 1 is a front, left side perspective view of a handheld ultrasonic display device with cover, showing our new design, with the cover in open position;

FIG. 2 is a front, left side perspective view thereof, in partially open condition;

FIG. 3 is a front, left side perspective view thereof, in fully closed position;

FIG. 4 is a front elevational view of FIG. 1;

FIG. 5 is a rear elevational view of FIG. 1;

FIG. 6 is a left side elevational view of FIG. 1, the right side elevational view being a mirror image;

FIG. 7 is a top plan view of FIG. 3; and,

FIG. 8 is a bottom plan view of FIG. 3.
